United States Patent Office

Des. 196,482
Patented Oct. 8, 1963

196,482

NOVELTY VEST

Clark E. Bentley, R.R. 1, Rushville, Ill., and Ray Clark
Montgomery, 402 E. 25th St., Hibbing, Minn.

Substituted for abandoned design application Ser. No.
65,780, June 14, 1961. This application Apr. 25, 1963,
Ser. No. 74,620

Term of patent 14 years

(Cl. D3—4)

FIG. 1

FIG. 2

FIG. 3.FIG. 4FIG. 1 is a front perspective view of a novelty vest showing our new design;

FIG. 2 is a rear perspective view thereof;

FIG. 3 is a front perspective view of another embodiment of the novelty vest shown in FIGS. 1 and 2 wherein the portrait-bearing links are chamfered squares; and

FIG. 4 is a rear perspective view thereof.

The essential features of our design reside in the full line disclosure on the drawing.

The dot-dash line showing of a garment is for purposes of illustration only.

We claim:

The ornamental design for a novelty vest, substantially as shown and described.
